(57) **CLAIM**

The ornamental design for a surgical clamp, as shown and described.

DESCRIPTION

FIG. 1 is a top, front, right side perspective view of a surgical clamp according to one embodiment of the present disclosure.

FIG. 2 is a bottom, rear, left side perspective view of the surgical clamp shown in FIG. 1.

FIG. 3 is a front elevation view of the surgical clamp shown in FIG. 1.

FIG. 4 is a rear elevation view of the surgical clamp shown in FIG. 1.

FIG. 5 is a left side elevation view of the surgical clamp shown in FIG. 1.

FIG. 6 is a right side elevation view of the surgical clamp shown in FIG. 1.

FIG. 7 is a top plan view of the surgical clamp shown in FIG. 1.

FIG. 8 is a bottom plan view of the surgical clamp shown in FIG. 1.

FIG. 9 is a top, front, right side perspective view of a surgical clamp according to another embodiment of the present disclosure.

FIG. 10 is a bottom, rear, left side perspective view of the surgical clamp shown in FIG. 9.

FIG. 11 is a front elevation view of the surgical clamp shown in FIG. 9.

FIG. 12 is a rear elevation view of the surgical clamp shown in FIG. 9.

FIG. 13 is a left side elevation view of the surgical clamp shown in FIG. 9.

FIG. 14 is a right side elevation view of the surgical clamp shown in FIG. 9.

FIG. 15 is a top plan view of the surgical clamp shown in FIG. 9; and,

FIG. 16 is a bottom plan view of the surgical clamp shown in FIG. 9.

The features shown in broken lines in FIGS. 1-14 form no part of the claimed design.

1 Claim, 8 Drawing Sheets
